UNITED STATES PATENT OFFICE.

KLEMENS DOMBELEK, OF NEW CASTLE, PENNSYLVANIA.

RAIL-CHAIR.

1,108,069.

Specification of Letters Patent. Patented Aug. 18, 1914.

Application filed November 12, 1913. Serial No. 800,618.

To all whom it may concern:

Be it known that I, KLEMENS DOMBELEK, a subject of the Emperor of Austria-Hungary, residing at Rigby, New Castle, in the county of Lawrence and State of Pennsylvania, have invented certain new and useful Improvements in Rail-Chairs, of which the following is a specification, reference being had therein to the accompanying drawing.

10 This invention relates to rail chairs, and has for its object to provide a device of such class, in a manner as hereinafter set forth, for not only supporting the meeting ends of a pair of rails, but for also connecting the 15 said ends together at the same time allowing for the necessary contraction and expansion of the rails.

Further objects of the invention are to provide a rail chair, which is simple in its 20 construction and arrangement, readily positioned, efficient in its use, strong, durable and inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood 30 that changes, variations and modifications can be resorted to which come within the scope of the claim hereunto appended.

In the drawings, wherein like reference characters denote corresponding parts throughout the several views:—Figure 1 is a side elevation of a rail chair in accordance with this invention, showing the adaptation thereof in connection with a pair of rails, Fig. 2 is an end view, Fig. 3 is an inverted 40 plan, Fig. 4 is a cross section, Fig. 5 is a longitudinal sectional view of one of the chair sections, Fig. 6 is an inverted perspective of one of the chair sections, Fig. 7 is a view of one end of a rail showing one of the 45 base flanges provided with a notch.

Referring to the drawings in detail, 8 and 9 denote a pair of rails and each of said rails in proximity to each end has one of its base flanges provided with a notch 10 for a purpose 50 to be presently referred to.

The rail chair is formed from two interlocking sections, one section being designated by the reference character 10 and the other section by the reference character 11.

55 The bottom of the section 10 is indicated by

the reference character 12 and at one end formed with a longitudinally extending tongue 13, and at its other end with a lateral angle-shaped extension 14, the latter providing a pocket 15. The bottom of the section 11 is indicated at 16 and has one end provided with a longitudinally extending tongue 17 which, when the sections 10 and 11 are mounted in operative position extends into the pocket 15. The other end of the bottom 16 of the section 11 is provided with a lateral angle-shaped extension 18, which provides a pocket 19 for the tongue 13. The inner longitudinal edge of each of the bottoms 12, 16 extends at an inclination as indicated at 20. The tongue 13 is of greater width than the tongue 17, and which tongue snugly fits the walls of its pockets. Formed integral with the bottom 12 is an inwardly extending member 21, and formed integral with the bottom 16 is an inwardly extending member 22. The members 21 and 22 overlap the base flanges 23 of the rails 8, 9, the latter being provided with notches 23'. The members 21, 22, in connection with the bottoms 12, 16, provide pockets 24 for the base flanges 23, and the inner wall of the pocket 24 in the section 10 is provided with a pair of integral spaced rounded lugs 25, which extend into the 85 notches 23' of the rails 8, 9, thereby preventing longitudinal movement of said rails. The lugs 25 snugly fit the notches 23'.

To prevent lateral movement of the chair, the latter may be of a length to be secured to only one tie or of a length to be secured to a pair of ties, the section 10 is notched as at 26, and the section 11 notched as at 27 and through the notches 26, 27, are adapted to extend spikes or other devices for fixedly 90 securing the chair to a tie or a pair of ties.

When setting up the chair in position, the section 11 is mounted upon the base of the rails 8, 9, after which the section 11 is slid upon the rails and interlock with the section 10.

What I claim is:—

A rail chair formed of a pair of sections having a body portion and inwardly extending members forming a pocket for the reception of the base flange of a rail, the said sections at the bottom portions being provided with a longitudinally extending tongue and a pocket, the latter being adapted for the reception of the tongue of 110

the other section, the tongue of one section being of greater width than the tongue of other section, said bottoms abutting and with the abutting edges thereof extending at an inclination, one of said sections being formed with a pair of spaced rounded lugs disposed below its respective inwardly extending member and being adapted to project into the base flanges of a pair of rails

so that the same are connected together by 13 said section.

In testimony whereof I affix my signature in the presence of two witnesses.

KLEMENS DOMBELEK.
